UNITED STATES PATENT OFFICE.

JOHN P. CRAVEN, OF ELIZABETH, NEW JERSEY.

MINER'S PICK.

1,076,103.

Specification of Letters Patent.

Patented Oct. 21, 1913.

Application filed April 26, 1913. Serial No. 763,901.

To all whom it may concern:

Be it known that I, JOHN P. CRAVEN, a citizen of the United States, residing at Elizabeth city, in the county of Union and

5 State of New Jersey, have invented certain new and useful Improvements in Miners' Picks, of which the following is a specification, reference being had to the accompanying drawings.

10 This invention relates to miners' picks and has for an object to provide an extremely simple and inexpensive pick which will have the detachable points that are secured in place without the use of set screws 15 or other similar fasteners.

A further object of the invention is to provide an extremely simple means for so securing the detachable points that the same may be applied or released by simply rotating the pick handle.

20 A further object of the invention is to provide a device of this character that will be strong and durable and will be formed of a few parts that will not easily get out 25 of order.

With the above objects in view the invention consists of certain novel details of construction and combination of parts herein-after fully described and claimed, it being 30 understood that various modifications may be made in the minor details of construction within the scope of the appended claim.

35 In the accompanying drawing illustrating this invention:—Figure 1 is a side elevation of the invention with parts in section. Fig. 2 is a plan view with parts in section. Fig. 3 is a detail plan view of the locking device.

40 Referring now to the drawing in which like characters of reference designate similar parts, 10 designates the pick head which is provided with a threaded central opening 11 to receive the reduced threaded end 12 of a cylindrical metal handle 13 that is pro-

45 vided with a wood grip 14 or other suitable grip. At the base of the threaded end 12 of the handle there exists an annular shoulder 15 the purpose of which will presently appear.

50 Formed in each end of the head is an opening 16 which loosely receives the cylindrical stem 17 of a cutting point 18, and also formed in the head at right angles to the opening 16 at each end of the head is 55 a key opening 19 which communicates with

the opening 16 and opens through that edge of the head next adjacent to the handle, these key openings 19 being disposed on opposite sides of the handle as shown.

60 The device for removably securing the points 18 in position is carried by and operated by the handle, and consists of a resilient cross arm 20 having a centrally disposed opening 21 to receive the threaded end 12 of the handle, and having integral up-turned key lugs 22 at the ends adapted to enter the openings 19 in the head and bear against the stems 17 of the points 18. The cross arm bears against the above described shoulder 15 on the handle, and when 65 the handle is advanced into the head this shoulder forces the resilient cross arm toward the head with a resultant urging of the key lugs against the stems of the points whereby the latter are firmly held against 70 escape from the head. Upon retracting the handle by unscrewing two or three turns more or less, the tension of the cross arm will be relieved whereby the key lugs release 75 the points for removal.

80 From the above description it will be seen that I have provided an extremely simple tool of the class described which will be formed of a few parts that will not easily get out of order. It will furthermore be seen that the removable points are secured in position without the use of set screws or similar fasteners, and further that by simply screwing the handle forward or 85 back in the head the points may be firmly secured against escape or released for removal, such operation requiring minimum time and minimum manual exertion. A tool constructed as above described is devoid of 90 any parts which might become lost as all the various parts are so assembled as to preclude any possibility of escape from their assembled positions.

95 What is claimed, is:—

100 A tool including a head having a threaded central opening therein, a handle having a threaded reduced extension for engagement in the threaded opening in said head, said extension forming a resultant shoulder on said handle, said head having a recess 105 formed in each end thereof, removable bits having reduced stems fitted in the recesses in the opposite ends thereof, a resilient member having a central opening therein mounted on the reduced threaded extension 110

of said handle and resting against said shoulder, said member having reduced extensions on opposite sides thereof, offset lugs formed on the extremities of said extensions for engagement in the openings in the lower face of the head, said lugs being adapted for frictional engagement with the stems disposed in the recesses in the opposite

ends of the head, as and for the purpose described.

In testimony whereof I hereunto affix my signature in the presence of two witnesses.

JOHN P. CRAVEN.
